WRITING INSTRUMENT

David Kahn, Englewood Cliffs, N.J., assignor to David Kahn, Inc., North Bergen, N.J., a corporation of New Jersey

Application March 13, 1957, Serial No. 45,242

Term of patent 14 years

(Cl. D74—17)

FIG. 1

FIG. 2

FIG. 3

FIG. 4

Fig. 1 is a front elevational view of the writing instrument embodying my new design;

Fig. 2 is a side elevational view thereof;

Fig. 3 is a rear elevational view thereof; and

Fig. 4 is a top plan view.

The characteristic feature of my design resides in the combination on the pen disclosed of the specific lined bands which are substantially equally spaced on the upper portion of the writing instrument casing and confined within the longitudinally extending portion of the clip, all as shown.

I claim:

The ornamental design for a writing instrument, substantially as shown and described.
